(57) **CLAIM**

The ornamental design for a base end cap for a segmented stator, as shown and described.

DESCRIPTION

FIG. 1 is a top view of a base end cap for a segmented stator, showing our new design.

FIG. 2 is a bottom view thereof.

FIG. 3 is a front view thereof.

FIG. 4 is a back view thereof.

FIG. 5 is a side view thereof.

FIG. 6 is another side view thereof; and,

FIGS. 7 through 9 are perspective views of the end cap showing environmental structure.

The broken lines showing the environmental structure in FIGS. 1 through 9 are for illustrative purposes only and form no part of the claimed design.
